SHINGLE

Harry H. Honigbaum, Forest Hills, N. Y.

Application October 20, 1934, Serial No. 749,291

9 Claims. (Cl. 108—7)

This invention relates to shingles adapted to be made primarily from composition roofing material, although it may be incorporated in any other material and may be in the form of a strip shingle or an individual shingle as desired.

The object of the invention is to so construct the shingle that the weather edge thereof is held down with reference to one or more shingles of an underlying course through the provision of cut outs so formed that they will interlock with openings or tongues formed in the body of the underlying shingle. All of the shingles are made the same so that when the shingles are laid in courses, they will interlock in the manner described to 10 securely hold down the weather edges of the respective shingles in a manner to preclude curling of the shingles or flapping of the shingles on the roof in the wind.

Features of the invention, other than those adverted to will be apparent from the hereinafter detailed description and claims, when read in conjunction with the accompanying drawing.

The accompanying drawing illustrates different practical embodiments of the invention, but the constructions therein shown are to be understood as illustrative, only, and not as defining the limits of the invention.

Figure 1 is a face view showing four shingles embodying the present invention laid in two successive courses in interfitting relation for the purposes specified.

Figure 2 is a fragmental perspective of a portion of one of the shingles shown in Figure 1.

Figure 3 is a similar view showing the manner in which one of the tongues is deflected out of the plane of the shingle to interlock with a similarly formed tongue in the showing of Figure 2.

Figure 4 shows the manner in which the two latter tongues interlock in order to hold down the weather edge of the shingle.

Figure 5 shows a modified form of shingle embodying the present invention.

Figure 6 shows two of these shingles interlocked with respect to one another.

Figures 7, 8, and 9 show further modified forms of the invention.

In making the shingle of Figures 1—4, I cut the same in a manner very similar to that employed in ordinary strip shingles of the "four-in-one" type, the same being provided with cut outs 1 to produce the effect of four shingle flaps in strip relation. At the base of each of these cut outs, I provide an upstanding tongue 2 which extends up into the cut out 1 in the plane of the shingle strip. Between each two cut outs 1 and above the upper

edges 3 thereof and in spaced relation to adjacent cut outs, I make cuts or cut outs of substantially U shape to form tongues 4 also in the plane of the body of the shingle.

When a shingle is thus formed with the respective tongues properly spaced for cooperation with one another, a plurality of such shingles may be laid as indicated in Figures 1 and 4. That is to say, the tongues 2 at the bases of the cut outs 1 are adapted to interfit with the tongues 4 interspaced above the cut outs, as shown in Figure 4, so that the tongues 4 will serve to hold down the weather edges 5 of the shingle strip at spaced apart intervals along such edge.

In practice, I may, if desired, eliminate the 15 tongues 2 at the base of the cut outs 1 and form the shingle strip as shown in Figures 5 and 6 so that the tongues 4 will hook over the lower edges of the openings 1, as shown in Figure 6, and thereby hold down the weather edges 5 of the shingle. 20 As an alternate construction, tongues 2 may be formed at the base of the cut outs 1 and may be passed through openings 6 instead of interfitting with the tongues 4 as shown in Figure 7.

In the preceding figures, the lower edge of the 25 strip shingle is continuous, but if desired the shingle elements of the strip may be divided at the center of the cut outs 1 along lines 7, as shown in Figure 8, the tongues 2 being divided by the cuts 7. The tongues will nevertheless function in the 30 same manner as disclosed in the previous figures.

The invention has furthermore heretofore been referred to as utilized in a strip shingle, but it may be utilized in individual shingles; as shown in Figure 9, wherein the tongues 2 are adapted to cooperate with the tongues 4. The individual shingle may, however, be made according to any of the foregoing constructions. It will be noted, however, that in all of the several figures of the drawing, the underlying principle is the same, 40 namely, that there is an interlocking relation between the edge of each cut out of one shingle and an opening within the confines of the body of an underlying shingle and above the cut outs of the latter, so that there is no tendency to leakage and a thoroughly tight roof is produced. The weather edges of the shingles are nevertheless held down firmly to the roof so that they cannot flap or curl.

The shingles are manufactured with the several tongues in the plane of the shingle, but the 50 tongues are so constituted that they may be readily deflected from the plane when the shingle is laid in order to cooperate with the interfitting relation hereinbefore described.

The foregoing detailed description sets forth 55

the invention in its preferred practical form and the invention is to be understood as fully commensurate with the appended claims.

Having thus fully described the invention, what I claim as new and desire to secure by Letters Patent is:

1. A shingle provided with cut outs in the weather portion of the shingle extending from points in spaced relation to and in a direction away from the weather edge thereof and spaced laterally apart to form an intermediate shingle tab in the weather portion of the shingle, said shingle being also provided beyond and between the upper ends of said cut outs and within the body of the shingle and spaced from the edges thereof with another cut out, one of said cut outs being formed to provide at the edge thereof a tongue adapted to be projected over the edge of another cut out of another shingle of the same kind when the shingles are laid in courses on a roof to hold down the weather edge of the overlying shingle.
2. A shingle provided with a set of spaced apart cut outs extending from points in spaced relation to and in a direction away from the weather edge thereof and in the normally exposed weather portion of the shingle and spaced laterally apart to form an intermediate shingle tab in the weather portion of the shingle, said shingle being also provided with an additional set of cut outs above and spaced between the cut outs of the other set within the body of the shingle and spaced from the edges thereof, each of the cut outs of one set being formed at one of its margins with a tongue adapted to extend through a cut out of another shingle of the same kind when the shingles are laid in courses on a roof to hold down the weather edge of the underlying shingle.
3. A shingle provided with laterally spaced apart tongues adjacent to and extending in an upward direction away from the weather edge thereof and also provided with a downwardly extending tongue above and spaced between the upwardly extending tongues within the body of the shingle and spaced from the edges thereof, one of said upwardly extending tongues being adapted to extend under the downwardly extending tongue of another shingle of the same kind when the shingles are laid in courses on a roof.
4. A shingle provided with laterally spaced apart cut outs extending from points in spaced relation to and in a direction away from the weather edge thereof to form the weather portion of the shingle into spaced apart tabs integrally united at the weather edges of the shingle, an upwardly directed tongue at the base of each cut out, said shingle being also provided above the upper ends of the cut outs and between the same and spaced from all edges of the shingle with another tongue facing in a downward direction, one upwardly directed tongue at the base of each cut out being adapted to cooperate with a downwardly facing tongue within the body of another shingle of the same kind when the shingles are laid in courses on a roof to hold down the weather edge of the shingle of the overlying course.
5. A shingle provided with laterally spaced apart cut outs extending from points in spaced

relation to and in a direction away from the weather edge thereof to form the weather portion of the shingle into spaced apart tabs integrally united at the weather edge of the shingle, an upwardly directed tongue at the base of each cut out, said shingle being also provided above the upper ends of the cut outs and between the same and spaced from all edges of the shingle with an opening adapted to receive a tongue of another overlying shingle of the same kind when such shingles are laid in courses on a roof to hold down the weather edge of the overlying shingle. 5

6. A shingle provided with laterally spaced apart cut outs extending from points in spaced relation to and in a direction away from the weather edge thereof to form the weather portion of the shingle into spaced apart shingle tabs integrally united at the weather edge of the shingle, and a tongue located between said cut outs and extending in the direction of the weather edge of the shingle and adapted to engage with the lower edge of a cut out of an underlying shingle of the same kind when such shingles are laid in courses on a roof for the purpose of holding down the weather edge of the overlying shingle. 10

7. A shingle provided with laterally spaced apart cut outs extending from points in spaced relation to and in a direction away from the weather edge thereof, and a tongue located between said cut outs and extending in the direction of the weather edge of the shingle and adapted to engage with the lower edge of a cut out of an underlying shingle of the same kind when such shingles are laid in courses on a roof for the purpose of holding down the weather edge of the overlying shingle. 15

8. A strip shingle embodying a set of laterally spaced apart cut outs extending from points in spaced relation to and in a direction away from the weather edge thereof to divide the weather portion of the shingle into spaced apart shingle tabs, said shingle having an additional set of cut outs above and spaced between the cut outs of the other set and also spaced from all edges of the strip, the cut outs of one set being formed to provide tongues adapted to extend through the cut outs of the other set of another shingle of the same kind and interlock with the edges 20 of the latter cut outs for the purpose of holding down the weather edge of the overlying shingle strip when a plurality of such strips are laid in courses on a roof. 25

9. A roof embodying a plurality of shingles laid in overlapping courses, each shingle having a set of cut outs extending from points in spaced relation to and in a direction away from its weather edge and in the exposed portion thereof, and an additional set of cut outs formed 30 in the overlapped portion of the shingle and spaced from all edges of the shingle, the cut outs of one set being formed to provide at their edges tongues extending through the cut outs of the other set of one or more additional shingles 35 of the same kind in different courses and overlapping the edges of the latter cut outs for the purpose of holding down the weather edges of the shingles. 40
